UNITED STATES PATENT OFFICE.

JAMES BUCHANAN MITCHELL, OF NEW YORK, N. Y.

FOUNTAIN-PEN.

SPECIFICATION forming part of Letters Patent No. 373,677, dated November 22, 1887.

Application filed January 18, 1886. Serial No. 188,835. (No model.)

To all whom it may concern:

Be it known that I, JAMES BUCHANAN MITCHELL, of the city, county, and State of New York, have invented a new and useful 5 Improvement in Fountain-Pens, of which the following is a full, clear, and exact description, reference being had to the annexed drawings, forming part of this specification.

The object of my invention is to provide a 10 fountain-pen in which the ink will flow freely without escaping in such quantities as to smirch or blot the paper or soil the hands.

My invention consists in the hereinafter-described instrumentalities for attaining said objects.

In the accompanying drawings, Figure 1 is a side view of my fountain-pen. Fig. 2 is a view of a part of the same with the pocket of elastic rubber, which surrounds the pen and 20 lower part of holder, removed. Fig. 3 is a longitudinal section of the instrument with the point-cover in place. Fig. 4 shows the elastic pocket. Fig. 5 is a cross-section of the lower part of the barrel, showing the slots in which 25 the pen is held. Fig. 6 is a cross-section of the pen. Fig. 7 is a longitudinal section of a modified form of the point-cover.

A represents the barrel of the instrument, which may be composed of two joints or sections screwed together, as shown, in the lower 30 of which the pen B, which is preferably of a less concave or raised form than the pens in general use, is inserted and held by its longitudinal edges in the slots b.

35 e is an elastic fluid-tight pocket formed of the tube c' and the conical or tapering extension c" of the same, of elastic rubber or other flexible material, through which the point of the pen B projects. In the rear of the pen is 40 an imperforate diaphragm, D, which is constructed integral with the barrel and covers the cross-sectional area of the same. At either side of said diaphragm apertures e are formed in the body of the barrel.

45 The outer surface of the barrel is raised in that part of it through which those apertures which open into the reservoir are made in the form of a projection, which may be of any shape such that it can be distinctly felt through the 50 thin elastic tube c' by the fingers of the writer.

It will be seen that by this construction the

orifices e and the elastic tube c' together form a valve connecting the barrel-chambers on the two sides of the diaphragm D. When the elastic tube c' is transversely compressed over the 55 projection F between the thumb and finger, it rises in a slightly-bulging form or "buckles" over the apertures, forming a trough in its under surface, through which ink will pass toward the pen, escaping from the barrel above 60 the diaphragm D and re-entering below it. The projection F is not indispensable to the proper compression of the rubber for this purpose, but adds very greatly to the convenience and precision with which it can be accomplished by indicating the exact position of the 65 apertures e and preventing the thumb and finger from slipping toward each other over the convex surface of the barrel in the act of opening the valve. It will be seen that the 70 valve above described is formed by the apertured barrel and the tubular section c' of the elastic pocket e, independently of the tapering section c", as the ink, after passing below the diaphragm D, might be conveyed to the 75 point of the pen by a trough, tube, or other means, in combination with which the valve would still be of great use.

The pen may be of the form of the split-nibbed pens in general use; but I prefer that 80 it should be "raised" but little, so that it shall depart less from a flat form, and the space between the concave surface of the pen and the inner surface of the tapering pocket surrounding it shall be thin, in order that it 85 may retain ink by capillarity and prevent it from passing too freely to the point of the pen.

The pen may be held in position by a variety of means; but I prefer to insert it by its longitudinal edges in longitudinal slots b, 90 formed for the purpose on the inner surface of the tubular holder. When thus inserted, the pen is securely held and the following advantages are gained: When the holder is of hard rubber and a gold pen is crowded into 95 close contact with that material over its entire width, the sulphur combined with the rubber, as is well known to makers of gold pens, acts upon and penetrates the alloy of the pen, so that it becomes brittle and often cracks or 100 splits after a time under the pressure by which it is held in place in the holder. This evil is

obviated in my device, above described, because the pen comes in contact with the holder only at its edges, where it is held by a light pressure, and the surfaces exposed to the action of the sulphur are very small. This method of insertion has also the advantages of being simple and secure, and of bringing the point of the pen of flattened form approximately in the line of the axis of the tubular holder, which gives the writer a steadier and easier control of the pen than when it is inserted at one side of the holder in the ordinary manner. This device is obviously not confined to fountain-holders, but adapted to all tubular pen-holders.

In order to prevent the pocket *c* from being forced downward on the barrel and pen by the pressure of the hand, I form a band or projecting ring, *y*, at or near the foot of the barrel, over which the pocket *c* is tightly stretched, and thus held at a suitable distance above the point of the pen.

To protect the point of the pen from injury when not in use I provide a point-cover, *H*. Near the closed end of this point-cover I insert a partition or diaphragm, *h*, of any suitable material, through an opening in which the point of the pen shall project into a waste-chamber, *K*. The object of this chamber is to receive and retain any small amount of ink that may escape from the pen into the end of the point-cover when the pen is laid down or carried in the pocket, so that such ink may not quickly spread upward on the lower part of the holder and be communicated to the fingers when the pen is used. The partition might be of hard material and integral with the point-cover; but I prefer to make it of elastic rubber, so that the opening will adjust itself to the form of the pen projecting through

it. It may be secured in place by a variety of means, as by a ring of hard material crowded or screwed against it, as shown in Fig. 7; but I prefer to secure it by uniting with it a thick ring or short tube, *h'*, of elastic rubber, crowded 45 into the closed end of the point-cover, with the partition *h* attached to and extending over the end of the tube *h'*, that is nearest to the holder, as shown in Fig. 3.

I claim as my invention—

1. In a fountain-pen, the combination of the flexible tube *c'* with the barrel *A*, provided with the diaphragm *D* and apertures *e*, and having upon that part of its outer surface through which the apertures are made the 55 projection *F*, of any form such that it may be distinctly felt by the thumb and finger through the flexible tube *c'*, to the end that the position of the apertures *e* may thereby be recognized and the tube *c'* conveniently compressed over 60 them, as specified.

2. A point-cover for a fountain-pen, having within it a chamber for containing waste ink, formed by the insertion near its closed end of a partition, of elastic rubber or other suitable material, through an opening in which the point of the pen shall project into said chamber, substantially as described.

3. A point-cover for a fountain-pen, consisting of the tube *H*, closed at one end, combined 70 with the circular partition *h*, of elastic rubber, having a perforation or opening to receive the point of the pen, united with the thick tube *h'*, of elastic rubber, as and for the purpose specified.

JAMES BUCHANAN MITCHELL.
